UNITED STATES PATENT OFFICE.

LOUIS MANNSTAEDT, OF KALK, GERMANY.

DESIGN FOR A WINDOW-RAIL.

SPECIFICATION forming part of Design No. 25,442, dated April 28, 1896.

Application filed August 15, 1894. Serial No. 520,431. Term of patent 7 years. Patented in Germany May 18, 1893, No. 14,442.

To all whom it may concern:

Be it known that I, LOUIS MANNSTAEDT, partner of the firm of the FAÇONCISEN-WALZWERK L. MANNSTAEDT & Co., residing at Kalk, near Cologne, in the Province of Rhenish Prussia, Germany, have invented and produced a new and original Design for Window-Rails, (patented in Germany May 18, 1893, No. 14,442,) of which the following is a specification, reference being had to the accompanying drawings, showing a part thereof.

Figure 1 in the accompanying drawings is a cross-section through the window-rail. Fig. 2 is a perspective view of the same.

The leading feature of my design for window-rails consists in the double-anchor shape, having the central main web A and branching from its sides the two side arms B B, and below these the two other similarly-shaped side arms C C, the upper arms B B being slightly smaller than the lower ones.

What I claim is—

The design for a window-rail herein shown and described.

LOUIS MANNSTAEDT.
